UNITED STATES PATENT OFFICE.

FRANK H. FERAUD, OF GRANITE CITY, ILLINOIS.

PHONOGRAPH-LAMP.

1,310,564.

Specification of Letters Patent. Patented July 22, 1919.

Application filed October 21, 1918. Serial No. 258,938.

To all whom it may concern:

Be it known that I, FRANK H. FERAUD, a citizen of the United States, residing at Granite City, Illinois, have invented a certain new and useful Improvement in Phonograph-Lamps, of which the following is a full, clear, and exact description, such as will enable others skilled in the art to which it appertains to make and use the same.

10 This invention relates to a phonograph lamp of the type described in my pending application Serial No. 184,068, filed August 2, 1917.

One object of my present invention is to 15 provide a phonograph lamp which is so constructed that the upper part of the structure comprising the shade and reproducer arm can be revolved or turned into such a position that a record can be applied to or 20 removed from the record support by a person standing at either side of the lamp.

Another object is to provide a phonograph lamp in which the shade is so constructed that the entire shade, instead of merely the 25 top portion of the shade, can be moved into such a position that a record can be applied to or removed from the record support.

Figure 1 of the drawings is a vertical sectional view of a phonograph lamp constructed in accordance with my present invention; and

Fig. 2 is an enlarged horizontal sectional view, taken on approximately the line 2--2 of Fig. 1.

35 Referring to the drawings which illustrate the preferred form of my invention, A designates the standard of the lamp which can be of any preferred form and construction, B designates the shade of the lamp, C designates one or more lighting units, preferably incandescent lamp bulbs arranged inside of the shade B, D designates the motor of the phonograph or sound reproducing machine, E designates the turntable or rotatable record support of the phonograph and F designates the reproducer arm of conventional form which is equipped with a stylus or needle that acts upon the record (not shown) supported by the turntable E. In the form 45 of my invention herein illustrated the standard A of the lamp is so constructed that it serves as the horn of the sound reproducing machine, said standard being hollow and open at its lower end so as to permit the 50 sound to escape from the horn. The lamp

can either be of the table type or of the type that stands on the floor of a room, and the shade B can be of any preferred construction and design. It is essential, however, so far as one feature of my present invention is concerned, that the shade B be mounted in such a manner that the entire shade can be moved into an inoperative position to facilitate removing or applying a record to the record support, and it is essential, so far as another feature of my present invention is concerned, that the shade and reproducer arm be mounted in such a manner that they can be rotated or turned around the base A so as to enable a person to apply or remove 60 a record without changing his position relatively to the lamp. In the form of my invention herein illustrated the reproducer arm is connected with the horn or hollow standard A of the machine by means of a 65 conduit 2 that is revolvably mounted on said horn or standard A. Said conduit 2 can be mounted in various ways without departing from the spirit of my invention, but I prefer to provide the lower end of said conduit 70 with a tubular portion 3 that fits loosely in a bearing 4 mounted in the upper end portion of the standard A, the conduit 2 having a horizontally-disposed flange 3a that rests on a horizontally-disposed flange 4a on the 75 bearing 4 which laps over the upper end of the standard A. The tubular portion 3 of the conduit is prevented from moving upwardly 80 out of the bearing 4 by a pin or screw 5 in the bearing that projects into an annular 85 groove 6 in said tubular portion, and if desired, the tubular portion 3 can be provided with a stop 7 that strikes against the screw 5 when the conduit 2 is turned a certain 90 distance in either direction. The motor D 95 is suspended from a plate 8 carried by the conduit 2 and by a bracket 9 that projects laterally from said conduit, as shown in Fig. 1, and the shade B is pivotally connected at 10 to a part 11 that is stationary with respect to the conduit 2, said part 11 either consisting of a bracket that projects downwardly from the plate 8 or a bracket that is secured to the conduit 2. Any other preferred method can be used for rotatably 10 mounting the conduit 2 and for pivotally mounting the shade B, but it is essential that the pivot of the shade be located at such a point that the entire shade can be swung upwardly, as shown in broken lines in Fig. 1, 11

so as to permit the record to be easily removed from or applied to the record support.

A phonograph lamp of the construction above described has all of the good features and desirable characteristics of the phonograph lamp described in my pending application previously referred to, and it has the following characteristics which add greatly to its commercial value; namely, the entire upper part of the structure comprising the shade, record support and reproducer arm can be turned either to the right or left so as to bring them into the most convenient position for applying or removing a record, thus overcoming the necessity of the user changing his position, and the shade B can be of conventional form, owing to the fact that the entire shade is hinged or pivotally mounted.

Having thus described my invention, what I claim and desire to secure by Letters Patent, is:

1. A device of the character referred to, consisting of a lamp provided with a shade and a standard, and a sound reproducing machine comprising a motor and reproducer arm arranged inside of the shade of the lamp and revolvably mounted on the standard of the lamp.

2. A device of the character referred to, consisting of a lamp and a sound reproducing machine combined as a single unit, and means for enabling the sound reproducing machine and the shade of the lamp to be turned or revolved relatively to the standard of the lamp so as to facilitate removing or applying a record to said machine.

3. A device of the character referred to, consisting of a lamp and a sound reproducing machine combined as a single unit, the shade of the lamp and the reproducer arm of said machine being carried by a part that can be turned or revolved with relation to the standard of the lamp.

4. A device of the character referred to, consisting of a lamp and a sound reproducing machine combined as a single unit, and a revolvable part on the standard of the lamp that carries the shade of the lamp and the motor, record support and reproducer arm of the sound reproducing machine.

5. A device of the character referred to,

consisting of a lamp provided with a standard and a shade, a sound reproducing machine whose record support and reproducer arm are arranged inside of said shade, and a revolvable part on the standard of the lamp that carries the shade of the lamp and the essential parts of the sound reproducing machine.

6. A device of the character referred to, consisting of a lamp provided with a standard and a shade, a revolvable part on said standard to which said shade is pivotally connected, and a sound reproducing machine carried by said revolvable parts and having its motor, record support and reproducer arm normally hidden from view by the shade of the lamp.

7. A device of the character referred to, consisting of a lamp and a phonograph combined as a single unit, the standard of the lamp constituting the horn of the phonograph and the motor, record support and reproducer arm of the phonograph being carried by a part that is revolvably mounted on the standard of the lamp.

8. A device of the character referred to, consisting of a lamp and a phonograph combined as a single unit, the standard of the lamp constituting the horn of the phonograph, and a revolvable conduit on said standard which carries the motor of the phonograph and also serves to connect the horn with the reproducer arm of the phonograph.

9. A phonograph lamp, consisting of a lamp and a phonograph combined as a single unit, a part revolvably mounted on the standard of the lamp, a support on said part which carries the motor of the phonograph, and a connection between said part and the shade of the lamp.

10. A device of the character referred to, consisting of a lamp provided with a shade whose upper and lower portions are permanently connected together, and a sound reproducing machine provided with a record support that is arranged inside of the shade, the shade of the lamp being pivotally mounted so that the entire shade can be moved out of its normal position during the operation of applying or removing the record used in the machine.

FRANK H. FERAUD.
